US0D1003511S

(12) **United States Design Patent** (10) **Patent No.:** **US D1,003,511 S**
(45) **Date of Patent:** **** Oct. 31, 2023**

(54) **POUCH**

(71) Applicant: **Henkel AG & Co. KGaA**, Duesseldorf (DE)

(72) Inventors: **Katja Gerhards**, Duesseldorf (DE);
Matthias Sunder, Duesseldorf (DE);
Frank Meier, Duesseldorf (DE)

(73) Assignee: **Henkel AG & Co. KGaA**, Duesseldorf (DE)

(**) Term: **15 Years**

(21) Appl. No.: **29/771,859**

(22) Filed: **Feb. 25, 2021**

Related U.S. Application Data

(62) Division of application No. 29/610,375, filed on Jul. 12, 2017, now Pat. No. Des. 914,283.

(57) **CLAIM**

The ornamental design for a pouch, as shown and described.

DESCRIPTION

FIG. 1 is a front perspective view of a pouch embodying our new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines shown in the drawings represent portions of the pouch that form no part of the claimed design.

1 Claim, 4 Drawing Sheets
